PUMP

Garth P. Kennedy, Charles M. Corken, and Eldo D. Heim, Oklahoma City, Okla., assignors to Corken's Inc., Oklahoma City, Okla., a corporation of Oklahoma Filed Apr. 7, 1958, Ser. No. 726,755
3 Claims. (Cl. 103—136)

This invention relates to pumps and particularly to improvements in the construction and operation of pumps and especially, a rotary pump.

The ordinary sliding vane rotary pump has been available for a number of years. The same principles of operation have been relied on to deliver fluid from an inlet through a pump chamber to an outlet. This invention provides improvements for the construction of such pumps and the ensuing operation is correspondingly improved. One of the objects of this invention is to provide a pump with cartridges that each contain a bearing and at least one seal for the support and sealing of the pump shaft. In a rotary pump bearing loads are important. In order to easily install and remove for servicing the bearing, this pump has made it possible to merely remove a single bearing cap for each cartridge, and then slip the cartridge from the cavity within which the cartridge is ordinarily supported. An appreciable saving in time, labor and money is achieved by having the bearings and retainers in the form of cartridges that are easily removed from the pump and easily replaced.

In the operation of a pump, it occasionally happens that the pump outlet becomes closed or blocked for one reason or another. The result is that the pump becomes unloaded and runs hot. Sometimes the fluid being pumped vaporizes and the pump operates under a vapor locked condition. Either condition is detrimental to the pump. A further object of the invention is to provide an external by-pass which connects with the pump chamber preferably near the outlet of the pump. This by-pass is connected to the pump supply so that there is always a small amount of recirculation. The purpose is to recirculate a small amount of fluid back to the supply tank in the event that the discharge side of the pump is closed for any reason. This small amount of fluid will permit the pump to operate at extended intervals with the discharge completely closed without overheating the pump and without causing the liquid being circulated to vaporize and thereby permit the pump to operate vapor locked.

An adjustable pressure opened valve is in the by-pass thereby enabling the quantity of fluid recirculated to be adjusted in accordance with pump pressure.

Although prior pumps have each had to be mounted on bases or mounting brackets, an important feature of this invention is an almost completely universal mounting bracket system. A specially constructed mounting bracket is arranged with the base and a support. The support may be attached to either side of the pump case or may be installed with the base under the pump or protruding laterally from the pump. Moreover, the means attaching the pump case to the upstanding support enable the pump case to be rotationally adjusted, and this is a great assistance in aligning a truck pump with the piping to and from a truck tank. Other objects and features of importance will become apparent in following the description of the illustrated form of the invention.

FIGURE 1 is an elevational view of the pump showing the fluid inlet side thereof.

FIGURE 2 is an end view of the pump in FIGURE 1.

FIGURE 3 is an elevational view showing one mechanical drive connected with the pump and showing the

2

pump mounted in one of a number of selected positions.

FIGURE 4 is an enlarged sectional view taken on the line 4—4 of FIGURE 2.

FIGURE 5 is a sectional view taken on the line 5—5 of FIGURE 4.

FIGURE 6 is an enlarged fragmentary sectional view showing a part of the by-pass including the by-pass valve of the pump.

FIGURE 7 is an exploded perspective view of one cartridge having a rotor shaft bearing and seal.

FIGURE 8 is an exploded perspective view of some of the parts which are assembled to form the pump.

In the accompanying drawings there is a pump 10. The illustration is of a sliding vane rotary pump whose major parts are in part shown in FIGURE 8. Referring first to these parts, there is pump case 12 together with heads or end pieces 14 and 16, one only shown in FIGURE 8. Rotor 18 has shaft 20 to which rotor body 22 is fixed. Radial slots 24 are in the body 22 and they accommodate vanes 26 capable of sliding in and out of the slots as the rotor is operated. Cam 28 has an inner surface over which the outer edges of vanes 26 are moved.

Side plates 30 and 32 have central apertures through which shaft 20 passes and they are on opposite sides of the cam 28. Head 14 is on one side of the case 12 while head 16 is on the other side and each is bolted in place. All confronting surfaces are sealed by O-rings or corresponding gaskets or gasket material where required. For example, O-ring 34 is fitted in a groove between a flange of head 14 and a part of the case 12 to seal head 14. An identical O-ring 36 seals head 16.

Two bearing cartridges or units 38 and 40 (FIGURE 4) are located in cavities 42 and 44 of heads 14 and 16. These are held in place by bearing caps 46 and 48 that are bolted to the outer ends of heads 14 and 16. Seals, for example, O-rings 49 and 50 are interposed between the bearing caps, the cartridges and heads to assure complete sealing at the junctions of these parts. Rotor shaft 20 to which rotor body 22 is keyed, for example by key 54, is mounted for rotation in the cartridges 40 and 38 and passes completely therethrough, leaving both ends of the shaft free for attachment with an external source of power. Splines, keyways or other conventional means for coupling the shaft 20 to the external source of power may be used.

There are two valves 56 and 58 respectively that are in registry with the pump chamber or passageway 60 in case 12. Valve 56 is a pressure relief valve which permits fluid under pressure near the pump outlet to return to the inlet part of chamber 60. Valve 58 constitutes a part of the by-pass 62 which bleeds a small quantity of fluid from the pump chamber 60 and returns it to the supply from which the fluid is being drawn. The purpose of the by-pass has been described previously.

Referring now to the pump in more detail, casing 12 is generally cylindrical. It has sides 66 and 68 whose faces form surfaces against which smooth faces of heads 14 and 16 abut. There are two pockets 70 and 72 that open inwardly of the case and which are separated by divider 74. Pocket 72 registers with the pump inlet 76 with which inlet conduits 78 is connected. Pocket 70 is registered with the outlet 80 that is adapted to be connected to any piping for delivering the pump fluid. The pump case 12 can be constructed of a casting with built-up parts at the inlet and outlets and also in the region of the relief valve 56 and by-pass 62. Plugs 81 and 82 are in openings in these last mentioned parts and they can be removed for receiving two pressure gauges, one indicating pump suction and the other indicating pump discharge pressure. The pockets 70 and 72 constitute a part of the pump chamber 60, this being in the

form of a passageway that communicates the pump inlet 76 with the pump outlet 80.

Cam 28 has rotor 18 installed in it. It is eccentric to the axis of rotation of shaft 20 and has two groups of slots 90 and 92 therein. The slots register respectively with pockets 70 and 72. The inside surface of the generally cylindrical cam 28 is smooth and has the outer ends of vanes 26 wiping thereon as the rotor is operated. End plates 30 and 32 are installed on opposite sides of the cam 28 (FIGURE 4) and are held in place by the inner ends of heads 14 and 16. Keyways 93, 94 and 95 are in the periphery of side planes 32 and 30 and cam 28. A key 96 is located in the keyways and anchored to the heads thereby preventing the cam and end plates 30 and 32 from rotating.

Heads 14 and 16 have bolting flanges by which they are attached to the case surfaces 66 and 68. They also have cylindrical parts 97 and 98 which form cavities 42 and 44 in which cartridges 40 and 38 are disposed. Excluding the installation of these cartridges 38 and 40, the next parts installed are the bearing caps 46 and 48. Each has a pair of grease relief openings 100 that ordinarily have plugs in them. They each have central openings accommodating grease retainers 102 and 104 through which the main shaft 20 of the rotor is passed.

Cartridge 40 slides into and is removable from cavity 42 by merely removing the bearing cap 46. The cartridge contains anti-friction bearing 110 that is mounted on the larger diameter part 112 of seal sleeve 114. Flange 116 of sleeve 114 has sleeve clamp collar 118 (FIGURE 8) bolted thereto with an O-ring and/or packing 120 on shaft 20 behind collar 118 and within a circumferential groove in the bore of sleeve 114. Bearing housing 124 fits over the bearing 110 and bearing housing retainer ring 126 is snapped into an annular groove formed in the side wall of housing 124 holding the bearing 110 assembled therein. Stop ring which is actually a bearing sleeve retaining ring 128 is fitted in a groove of sleeve 114 and abuts the inner face of the inner race of an anti-friction bearing 110 (FIGURE 4).

The reduced diameter part 132 of sleeve 114 accommodates a seal 136. The seal consists of a stationary face 140 with a stationary face O-ring 142 in a groove therein. Rotating face 146 in the form of a collar, is also fitted on the reduced diameter part 132 of the sleeve 114 and abuts the stationary face. Seal sleeve retainer ring 148 is on the end of sleeve 132, fitting in a groove therein. Packing or an O-ring 150, is located between ring 148 and the inner surface of rotating face 146. Cage 154 is on the rotating face 146 and is held in place and as a part of the rotating face of the seal by retaining ring 148.

Seal 146 excludes fluid from bearing 110 while the shaft 20 is amply sealed by retainer 102, O-ring 120 and the presence of sleeve 112 thereon.

Relief valve 56 (FIGURES 5 and 8) is constructed of a cylindrical valve element 160 which has the form of a cup. It is on valve seat 162 that is between the pressure and suction parts of the passageway or pump chamber 60. Spring 164 is disposed in the cup-shaped valve element 160 and abuts stop 166 that is supported on adjustment screw 168. The head of the screw contacts closure 170 over the open end of the relief valve chamber 172 thereby providing a reaction for the spring 164. The relief valve 56 is made in such a way as to discourage tampering by having the screw 168 concealed beneath closure 170. However, access plug 178 is in the closure 170 for the principal purpose of adjusting the pump relief valve 56 at the factory specification. Adjustment may be considered desirable when the pump handles fluids of different viscosity.

The by-pass valve 58 that constitutes part of by-pass 62 is of considerable importance. Conductor 180 is a passage that registers with the pump chamber 60 near the outlet 80 or at some other place in the high pressure part

thereof. The conductor 180 is communicated with an outlet 182 to which conduit 184 is attached. A pressure opened valve 186 functioning as relief valve 58, is in the network of conductors (FIGURE 6) and controls the passage of fluid from chamber 60 to the conduit 184. Valve 186 is made of a small case 188 threaded in bore 189 and having spring 190 disposed therein. One end of the spring is seated on shim 192 while the other end of the spring is seated on valve element 194. This element is constrained in its travel within bore 189 by abutting valve seat on shoulder 196 in this bore. A washer can be on the inner end of the valve element and constitute a part of it. Adjustment is achieved by altering the shims 192 and/or adjustment of small case 188.

15 The by-pass has a small quantity of the fluid conducted from chamber 60 and delivered to conduit 184 that connects to the supply. This assures that there will be at all times at least a small quantity of fluid handled by the pump regardless of where the outlet 80 is partially or even 20 fully closed.

25 In FIGURE 3 a typical pump installation is shown. The source 200 of power drivingly connects to shaft 20 by an extensible shaft 202 that is coupled at its ends to the power output shaft 204 and to pump shaft 20 respectively by universal joints and couplings. This figure shows that both ends of the pump have a part of shaft 20 available for driving a pump. Moreover, this figure shows only one method of mounting the pump. Mounting bracket 210 in this figure is shown more in detail 30 than FIGURES 1 and 2. It consists of a flat plate 212 that constitutes a support and which has a group of arcuate slots 214 near its periphery. There is a central aperture 216 through which the cylindrical part 98 of head 16 is passed. Bolts 218 are passed through the 35 slots 214 and are attached to the mounting flange of head 14. The bolts 218 can be long enough to enter tapped holes in the case 12. In either event the support is capable of holding the pump case in selected degrees of orientation with the limit being established by the length 40 of slots 214. This is of great assistance in aligning the pump with existing pipes, for example, on a truck.

45 Base 226 protrudes laterally from the lower part of the support. This base can be bolted down or can be otherwise fastened in place. Actually, the base may simply 50 rest on a supporting surface, these being alternative which will depend on the particular application of the pump. By having the base protrude essentially only from one side of support 212, the base can be reversed (see FIGURE 1) for left-hand and right-hand installation. This, coupled with the orientation adjustment of the pump case 55 enables the pump to be adjusted to an exceedingly large number of positions.

55 The pumping action takes place by movement of the rotor in cam 28 in a fashion that is well-known. The sliding vane rotary type pump has been common for a 60 number of years. The described pump, though has the improvements that have been pointed out and discussed. It is understood that this invention is not limited to the exact details of construction which are shown and described. All modifications that fall within the scope of the following claims may be resorted to.

65 What is claimed as new is as follows:

1. In a rotary pump which has a hollow open ended case provided with an inlet, an outlet, a conducting passageway communicating said inlet with said outlet and a sliding vane rotor to deliver fluid from said inlet into said passageway and through said outlet, a cam in said case having an inner surface over which the rotor vanes slide, said cam having passages which form a portion of said 70 passageway, side plates disposed over the opposite ends of said case on opposite ends of said rotor enclosing the latter within said case and having their confronting surfaces closely embracing the opposite ends of said rotor, each of said side plates having a central aperture formed 75 therein, removable end pieces secured to said case over

said side plates and securing the latter to said case, said end pieces having outwardly opening cavities in axial alignment with said side plate apertures, a rotor shaft connected to said rotor and extending through said apertures and having remote end portions thereof in said cavities, combined unitary bearing and seal cartridges removably received in said cavities and mounting said shaft for rotation, and outer bearing caps removably secured to said end pieces and forming cavity end closures comprising the sole means for enclosing said cartridges in said cavities, a support base carried by one of said end pieces for supporting said pump, a plurality of circumferentially spaced arcuate slots in said one end piece having the axis of rotation of said shaft as their center, fasteners secured through and slidably longitudinally of said slots and secured in said case, said inlet and outlet each having a longitudinal axis extending substantially at right angles to said shaft.

2. The combination of claim 1 wherein each of said unitary bearing and seal cartridges includes a bearing for journaling a part of said shaft and a fluid seal mounted inwardly of said bearing for excluding excess of the fluid being handled by said pump to said bearing.

3. The combination of claim 2 wherein each of said bearing caps is provided with lubricating means for maintaining the supply of lubricant for the corresponding bearing, and seal means in each of said caps outwardly of said lubricating means and engaging said shaft preventing the

entrance of foreign material into said bearing and the loss of lubricant from said bearing outwardly of said shaft.
